R. CHAFFEE.

GUTTER AND SCRAPER THEREFOR.

APPLICATION FILED SEPT. 6, 1918.

1,311,640.

Patented July 29, 1919.

UNITED STATES PATENT OFFICE.

RUSSEL CHAFFEE, OF WITHEE, WISCONSIN.

GUTTER AND SCRAPER THEREFOR.

1,311,640.

Specification of Letters Patent.

Patented July 29, 1919.

Application filed September 6, 1918. Serial No. 252,835.

To all whom it may concern:

Be it known that I, RUSSEL CHAFFEE, a citizen of the United States, residing at Withee, in the county of Clark and State of Wisconsin, have invented certain new and useful Improvements in Gutters and Scrapers Therefor, of which the following is a specification.

The present invention relates to an improved gutter construction which is adapted for use in stables and other buildings where horses and cattle are to be housed, the object of the invention being to provide a device of this character which will greatly facilitate the removal of refuse from the stable.

For a full understanding of the invention, reference is to be had to the following description and accompanying drawings, in which:

Figure is a plan view of a gutter constructed in accordance with the invention.

Fig. 2 is a transverse vertical sectional view.

Fig. 3 is a detail view of one end of the rock shaft and portions of the scraper and packer.

Corresponding and like parts are referred to in the following description and indicated in all the views of the drawings by the same reference characters.

The reference character A designates a stable floor which is supported in an elevated position by a frame B. An elongated opening C is formed in the floor at a convenient position therein, and arranged under the opening C is an elongated gutter M. This gutter is supported by transverse straps 5 which extend under the same, being curved to conform to the shape thereof, the ends of the straps being engaged by bolts 6 carried by plates L applied to the bottom of the floor A adjacent the opening C. These bolts 6 enable the gutter M to have a limited vertical adjustment, and it will be obvious that any refuse upon the stable floor can be readily scraped or swept toward the opening C so as to fall through the said opening into the gutter M.

A scraper F is arranged within the gutter M and extends longitudinally thereof, said scraper being carried by arms 7 which project laterally from the upper edge thereof and extend over the top of the gutter M. These scraper arms 7 are pivotally connected

at 8 to crank arms 9 which project downwardly from sleeves d³ and d⁶, said sleeves being slidable upon a rock shaft D which is arranged parallel to the gutter and journaled within suitable bearings E projecting from the stable floor. These bearings E have slotted bases which are secured in position by the screws 19, thereby enabling the bearings to have a limited adjustment toward and away from the floor opening C. The sleeves d³ and d⁶ are provided with longitudinal slots which are adapted to be moved into and out of engagement with lugs d⁷ and d¹⁰ projecting from the shaft D. A bar 10 connects the sleeves d³ and d⁶, and a link 11 is shown as engaging the bar 10 for convenience in sliding the sleeves d³ and d⁶ on the rock shaft D to bring the same into and out of interlocking engagement with the lugs d⁷ and d¹⁰. A handle I is shown as applied to one end of the rock shaft D for operating the same, and it will be obvious that by manipulating the handle when the sleeves d³ and d⁶ are locked with the shaft the scraper F will be moved transversely back and forth within the gutter M.

This movement of the scraper F will force the refuse which may have collected in the gutter M over the longitudinal side edges thereof, and this discharged refuse will drop into a suitable receptacle such as a car K which is arranged under the gutter. The car is shown as mounted to travel upon the tracks g, and a packer P is shown as arranged within the body of the car and mounted for back and forth movement therein. This packer P is normally arranged in a vertical position and is provided at its upper edge with laterally projecting arms 12 which are detachably connected by fastening members 13 to links 14. These links 14 have an adjustable pivotal connection 15 with the lower ends of crank arms 16 which project downwardly from sleeve d⁴ and d⁵ on the rock shaft D. Said sleeves d⁴ and d⁵ are formed with longitudinal slots which are adapted to be moved into and out of interlocking engagement with the lugs d⁸ and d⁹ projecting from the shaft D. A bar N connects the sleeves d⁴ and d⁵ for obtaining a simultaneous movement thereof, and it will be obvious that when the sleeves are moved into an interlocking engagement with the lugs d⁸ and d⁹ the packer P will be reciprocated back and forth.

forth within the car K when the rock shaft D is operated. On the other hand, when the sleeves d^4 and d^5 are disengaged from the corresponding lugs, the shaft can be operated independently of the packer P. In a similar manner, when the sleeves d^3 and d^6 of the scraper are disengaged from the corresponding lugs, the shaft D can be operated independently of the scraper. The packing means and scraping means are thus operatively connected to the same shaft and arranged so that they can be operated simultaneously or independently of each other, as may be desired. The packer P remains in the car, and when the car is loaded and ready to be moved the packer arms 12 are disengaged from the links 14 by removing the fastening members 13.

What I claim as new is:—

- 20 1. The combination with a stable floor having an opening therein, of an elongated gutter supported under the opening, a scraper extending longitudinally of the gutter, a rock shaft arranged parallel to the gutter, crank arms projecting from the rock shaft, and an operative connection between the crank arms and the scraper for moving the scraper transversely of the gutter to discharge the contents of the gutter over the longitudinal edges thereof.
- 25 2. The combination with a stable floor having an opening therein, of an elongated gutter supported under the opening, a scraper extending longitudinally of the gutter, a rock shaft arranged substantially parallel to the gutter, an operative connection between the scraper and the rock shaft, and means for breaking the connection between the rock shaft and the scraper, said scraper being movable transversely within

the gutter to discharge the contents of the gutter over the longitudinal edges thereof.

3. The combination with a stable floor having an opening therein, of an elongated gutter supported under the opening, a 45 scraper extending longitudinally of the gutter, means for moving the scraper transversely within the gutter to discharge the contents of the gutter over the longitudinal edges thereof, a receptacle under the gutter, 50 and packing means within the receptacle.

4. The combination with a stable floor having an opening therein, a gutter arranged under the opening, a scraper for the gutter, a receptacle for receiving the refuse 55 matter discharged from the gutter, a packer for the receptacle, an operating shaft, a clutch controlled operative connection between the shaft and the scraper, and an independent clutch controlled operative connection between the shaft and the packer, the scraper and packer being thus adapted to be operated from the shaft either simultaneously or independently of each other.

5. The combination with a gutter, a 65 scraper for the gutter, a receptacle arranged to receive the refuse discharged from the gutter, a rock shaft having lugs projecting therefrom, a set of slotted sleeves mounted upon the shaft and adapted to be moved into 70 and out of interlocking engagement with certain of the lugs, an operative connection between the sleeves and the scraper, a second set of slotted sleeves mounted upon the rock shaft and adapted to be moved into and out of engagement with others of the lugs, and an operative connection between the second set of sleeves and the packer.

In testimony whereof I affix my signature.
RUSSEL CHAFFEE.
